United States Patent Office.

D. H. JENNINGS AND JAMES BOUNDS, OF BRIDGEPORT, CONNECTICUT.

Letters Patent No. 91,749, dated June 22, 1869.

IMPROVED BEDSTEAD.

The Schedule referred to in these Letters Patent and making part of the same.

To all whom it may concern:

Be it known that we, D. H. JENNINGS and JAMES BOUNDS, of Bridgeport, in the county of Fairfield, and State of Connecticut, have invented certain new and useful Improvements in Invalid-Bedsteads; and we do hereby declare that the following is a full, clear, and exact description thereof, reference being had to the accompanying drawings, and to the letters of reference marked thereon, which form a part of this specification, in which the drawing represents a longitudinal section of our bedstead with one side removed.

The nature of our invention consists in constructing and attaching to a bedstead an adjustable frame, by which the body of an invalid can be raised or lowered without disturbing his lower limbs, the said object being effected by means of a geared shaft operating on levers in the manner set forth.

A represents a section of the bedstead.

C designates the stationary slats, which are secured in position in the ordinary way.

D is a bar, the lower end of which is pivoted to the inside of the rail E, a similar bar being pivoted on the opposite rail of the bedstead.

d d are slats, the ends of which are secured to bars D D.

F represents an arm, pivoted at its upper end to bar D, each bar being furnished with an arm.

g designates a shaft, the ends of which rest in bearings fastened to the bed-posts directly under the side rails.

On the said shaft is hung the pinion h.

m designates a second shaft, which has its bearings

on the inner side of the bed-post, and at right angles with shaft g. On the inner end of shaft m, is the worm-wheel s, which gears into pinion h.

On the outer end of shaft m is fastened the wheel N, by which said shaft is operated.

e represents a cord, one end of which is secured to the lower end of arm F, and the other end fastened to the shaft g, a similar cord being also attached to the opposite arm F.

The cords e, it will be observed, are made sufficiently long to admit of the bars D descending to a horizontal position; and when it is desired to elevate the body of the invalid, by turning the wheel N from left to right, the worm-wheel s will act on pinion h, and give motion to shaft g, so that the cord e will be wrapped around the said shaft, and thus draw the arms F upward.

By the elevation of the arms, the bars D can be raised to any desired angle to accommodate the invalid.

Having thus described our invention,

What we claim, and desire to secure by Letters Patent, is—

The combination of shafts m g, wheel N, pinion h, arm F, cords e e, and lever D, when all are arranged to operate as described.

In testimony that we claim the foregoing as our own, we affix our signatures, in presence of two witnesses.

JAMES BOUNDS.

D. H. JENNINGS.
